UNITED STATES PATENT OFFICE.

DORMER WALSH, OF SAN FRANCISCO, CALIFORNIA, ASSIGNOR OF ONE-HALF
TO FLETCHER H. MANKER, OF SAME PLACE.

GAME.

SPECIFICATION forming part of Letters Patent No. 433,110, dated July 29, 1890.

Application filed May 21, 1890. Serial No. 352,644. (No model.)

To all whom it may concern:

Be it known that I, DORMER WALSH, a citizen of the United States, residing in the city and county of San Francisco, State of California, have invented an Improvement in Games; and I hereby declare the following to be a full, clear, and exact description of the same.

My invention relates to a novel improvement in games or toys.

It consists of an inclosed table having a smaller movable table fixed in it with the upper surface flush with that of the main table, a means for giving an impulse to the movable table, and a series of marked or numbered pieces which are assembled upon the movable table and afterward projected therefrom, and an opening in the main table designed to receive some one of the marked disks which are projected from the movable table and to expose the number or mark thereon.

Referring to the accompanying drawings for a more complete explanation of my invention, Figure 1 is a top view of my device. Fig. 2 is a bottom view of the same. Fig. 3 is a vertical section.

A is a plane surface or table, which may be made of any suitable size or shape, and it has a rim B around its periphery and a glass cover situated a sufficient distance above the table A to allow disks or pieces of wood, pasteboard, or other material C to lie upon the table beneath the glass and to slide easily about the table beneath the glass cover. At some convenient point in the table is made an opening D, the size of which is sufficient to receive any one of the disks or pieces C, and in the bottom of this opening may be fixed a piece of glass, through which the bottom of any of the disks which are in the opening may be seen, or, if preferred, a flange or ring may be fixed in the bottom of the opening of smaller diameter than the disks, so that the disks may be seen through this opening, but cannot be removed. Each of the disks has a number or character upon the lower surface, which character is invisible from above and can only be seen when one of the disks has been placed in the opening above described. At some other convenient part of the table an opening is made, into which a circular disk

E is placed, the upper surface of the disk being approximately flush with the surface of the table A. This disk E is so constructed as to be rotatable about its axis, and it has 55 in the present case a bar F fixed transversely across its center and rising a little above the surface of the disk. The disk is provided with a knob or handle G, which projects from the center of the lower part so that it may 60 be grasped by the thumb and finger, and a spring H, of any suitable construction, is so connected with the disk that when the disk is turned about by means of the knob and then released the spring will return it with 65 considerable force to its original position. It will be manifest that this spring may be made of elastic stretched across the opening beneath the disk E and connected with the shank of the knob so that when this knob is 70 turned partly around the elastic will pull from opposite sides, and thus act to return the disk to its proper position, or a spiral or other spring may be employed, the object in either case being to return the disk E abruptly to 75 its original position after it has been turned out of that position and the knob released.

The small-numbered disks C are assembled upon the movable rotary table E by shaking the main table A in the hand until they are 80 assembled upon this table E, and the latter is then turned by means of the knob as far as may be necessary to give the spring a sufficient effect upon the table. The knob being released, the table will be rapidly returned 85 to its original position, and the momentum thus acquired causes the transverse bar or arms to scatter the movable-numbered disks about the surface of the main table beneath the glass, and some one of these disks may 90 be thrown into the hole or opening D in the main table, thus exposing the figure or character upon the lower surface. In connection with this various games may be played, in which the numbered disks decide certain features in the game, and when the disks have 95 been assembled upon the rotary table E and scattered about and one of them drops into the opening D so that the number can be read the result of the game may be ascertained by this number.

It will be manifest that various games may

thus be played by the use of this device, the object being in each case to scatter the movable disks about the main table and to place one of them within the observation-opening.

5 It will be manifest that various devices may take the place of the rotating disk E, the object being to provide a device in connection with the main table which will scatter the movable disks about the surface of this table 10 in an irregular manner.

Having thus described my invention, what I claim as new, and desire to secure by Letters Patent, is—

15 1. A device consisting of a table, independent movable disks or pieces adapted to slide upon said table and having numbers or characters upon their lower surfaces, a means in connection with said table whereby said disks may be violently projected and scattered over 20 the surface of the table, and an opening in said table through which the character or figure upon any disk may be observed when the latter is thrown over into the opening, substantially as herein described.

25 2. The toy or game consisting of the main table having a raised periphery and a glazed cover, a rotating table journaled in the main table with its upper surface flush with that of the latter, and a bar or projection extend-

30 ing above the surface of the rotating table, a means whereby said table may be turned about its axis, and a spring or device whereby it is abruptly returned to its normal position when released, substantially as herein described.

35 3. A toy or game consisting of a table having a raised rim around its periphery and a glazed surface or cover, a series of independent movable disks having numbers or characters upon their lower surfaces, an opening 40 in the main table through which the character upon any disk may be observed when the latter is placed over the opening, a rotary table journaled within the main table, a raised bar or flange upon said rotary table about 45 which the movable disks may be assembled upon the rotary table, a means for turning said table from its normal position, and a spring whereby the table may be abruptly returned to its normal position and scatter 50 the movable disks about the surface of the main table, substantially as herein described.

In witness whereof I have hereunto set my hand.

DORMER WALSH.
